(57) **CLAIM**

The ornamental design for a cleaning brush, as shown and described.

DESCRIPTION

FIG. 1 is a first perspective view of the first embodiment of a cleaning brush showing my new design;

FIG. 2 is a second perspective view of the first embodiment thereof;

FIG. 3 is a front view of the first embodiment thereof;

FIG. 4 is a back view of the first embodiment thereof;

FIG. 5 is a left side view of the first embodiment thereof;

FIG. 6 is a right side view of the first embodiment thereof;

FIG. 7 is a top view of the first embodiment thereof;

FIG. 8 is a bottom view of the first embodiment thereof;

FIG. 9 is a perspective view of another state of the cleaning brush thereof;

FIG. 10 is a first perspective view of the second embodiment of a cleaning brush showing my new design;

FIG. 11 is a second perspective view of the second embodiment thereof;

FIG. 12 is a front view of the second embodiment thereof;

FIG. 13 is a back view of the second embodiment thereof;

FIG. 14 is a left side view of the second embodiment thereof;

FIG. 15 is a right side view of the second embodiment thereof;

FIG. 16 is a top view of the second embodiment thereof;

FIG. 17 is a bottom view of the second embodiment thereof;

FIG. 18 is a perspective view of another state of the cleaning brush thereof;

FIG. 19 is an enlarged view of the selected portion 19 in FIG. 1;

FIG. 20 is an enlarged view of the selected portion 20 in FIG. 2; and,

FIG. 21 is an enlarged view of the selected portion 21 in FIG. 10.

The broken lines shown in the drawings depict portions of the cleaning brush that form no part of the claimed design.
